UNITED STATES PATENT OFFICE.

RUDOLPH CONRADER, OF ERIE, PENNSYLVANIA.

PUMP.

1,178,216.

Specification of Letters Patent.

Patented Apr. 4, 1916.

Application filed March 30, 1914. Serial No. 828,143.

To all whom it may concern:

Be it known that I, RUDOLPH CONRADER, a citizen of the United States, residing at Erie, in the county of Erie and State of Pennsylvania, have invented new and useful Improvements in Pumps, of which the following is a specification.

This invention relates to pumps and consists in certain improvements in the construction thereof as will be hereinafter fully described and pointed out in the claims.

One of the leading objects of the invention is to provide a pump adapted for pumping Artesian wells, such as oil wells, with means whereby sand or similar material carried with the liquid to be pumped is prevented from reaching the working contact surfaces of the pump.

The invention is illustrated in the accompanying drawings as follows:

Figure 1 shows a central section of a pump. Fig. 2 a similar section of the lower sand trap. Fig. 3 a section on the line 3-3 in Fig. 1. Fig. 4 a section on the line 4-4 in Fig. 1. Fig. 5 a section on the line 5-5 in Fig. 1. Fig. 6 a section on the line 6-6 in Fig. 1. Fig. 7 a section on the line 7-7 in Fig. 1. Fig. 8 an elevation, partly in section, of the discharge tube of the pump plunger.

1 marks the working barrel, 2 the standing valve, and 3 the plunger. The plunger is formed by a sleeve 4 having a shoulder 5 at its upper end. The cups 6, 8 and 10 have the spacing rings 7 and 9 between them. A spacing ring 11 is arranged below the lower cup 10 and a reverse cup 12 is arranged against the spacing ring 11. The cups are clamped in position by the plunger bottom 13.

The upper end of the sleeve 4 is screw threaded at 14 and the crown 15 is screwed on to the sleeve at 14. The plunger valve seat 16 is secured between the end of the sleeve 4 and the shoulder 17 on the crown, the seat being clamped in position as the crown is screwed to place. The ball check of the plunger 18 is arranged in the crown 15. A tube 19 is screwed into the upper end of the crown, the upper end of the crown forming a bottom 20 for the lower sand trap 22. The sand trap 22 forms a fairly close fit with the working barrel and is provided with perforations 21 which lead from the top of the crown to the bottom of the sand trap. Deflectors on guides extend upwardly

from the bottom of the sand trap 22, the guides having their apexes midway between the perforations 21 and terminating at such perforations. The purpose of these guides is to provide a slanting surface on which material being deposited in the cups falls and from which it is carried to the perforations 21.

The tube 19 is screwed into the collar 24, the collar 24 being internally and externally screw threaded. The discharge tube 25 is screwed into the collar 24. This has a cap 26 which has the sucker rod connection 27. The sand trap cup 28 is screwed on to the outside of the collar 24. The shoulder or ring 29 is screwed onto the upper end of the cup 28, the ring approximating the size of the tubing. It will be understood that the cup 28 is of considerable length and the drawings are broken indicating this. The bottom of the cup ordinarily enters the working barrel whereas the top of the cup or ring 29 does not. The top of the ring and cup have a beveled surface 30, the top of the bevel being the outer edge so as to direct the material being deposited from the column of liquid in the tubing into the cup.

Jet openings 31, are arranged in the tube 25. These jet openings are so shaped that the jet issuing from them has a downward and spiral direction. The purpose of this is to break up and carry out with each pumping the fine sand which may be deposited in the cup in the interval between pumpings. The direction of the jets is best calculated to effect this result. By arranging these jet openings at different levels the sand is gradually worked down so that the trap is cleared even though filled for many feet with sand. By extending this trap into the barrel and then above it into the tubing, a trap of any length desired may be used.

The lower sand trap is designed to catch any fine sand that may pass the upper trap, the fit of the upper trap being a loose one by reason of the fact that it operates in connection with the tubing. It will be noted that the ring 29 operating in connection with the tubing and having a larger diameter than the working barrel forms with the end of the working barrel a pump so that on the downward stroke of the pump plunger the space between the pump barrel and the upper end of the working barrel is diminished and the liquid in this space is forced out, some of it going out between the ring and the

tubing and some of it being forced down between the cup 28 and the walls of the working barrel through the trap 22 and by way of the perforations 21 to the main stream of liquid passing upwardly through the plunger. On the return stroke, there is a slight flow in the opposite direction. This flow of liquid through the perforations 21 and through the sand trap keeps the lower sand trap at all times clear of accumulations of sand and the result of these traps is to keep those surfaces in contact with the cups at all times clear of sand from above.

In order to lift the ball 18 on the downward stroke of the pump, considerable excess of pressure is required below the plunger over what there is above it by reason of the difference of the exposed areas of the valve due to the surface in contact with the seat. There is a tendency, therefore, for the liquid before the ball is lifted and during the excess of pressure below the ball to pass up along the outside of the cups. This is prevented in the present pump by the reverse cup 12 so that sand is prevented from reaching the cups both from below and above.

I do not claim in this application the specific structure of plunger shown in this application as this forms the subject matter of a separate application filed on even date with this application #828,144, nor do I claim in this application the specific structure of standing valve herein shown as it forms the subject matter of a separate application filed on even date with this application #828,145.

What I claim as new is:

1. In a pump, the combination of a working barrel; a plunger operating in the barrel; a sand trap; and a tube extending into the sand trap and adapted to convey liquid pumped by the plunger, said tube having spirally directed jet openings leading into the sand trap for delivering the liquid to the sand trap.

2. In a pump, the combination of a working barrel; a plunger operating in the barrel; a sand trap; and a tube extending into the sand trap and adapted to convey liquid pumped by the plunger, said tube having downwardly and spirally directed jet openings leading into the sand trap for delivering liquid to the sand trap.

3. In a pump, the combination of a working barrel; a plunger operating in the working barrel; a sand trap carried by the plunger; and a tube carried by the plunger and extending into the sand trap and adapted to convey liquid pumped to the sand trap, said tube having downwardly directed jet openings leading into the sand trap for delivering the liquid to the sand trap.

4. In a pump, the combination of a working barrel; a plunger operating in the work-

ing barrel; a sand trap carried by the plunger; and a tube carried by the plunger and extending into the sand trap and adapted to convey liquid pumped to the sand trap, said tube having spirally directed jet openings leading into the sand trap for delivering the liquid to the sand trap.

5. In a pump, the combination of a working barrel; a plunger operating in the working barrel; a sand trap carried by the plunger; and a tube carried by the plunger and extending into the sand trap and adapted to convey liquid pumped to the sand trap, said tube having downwardly and spirally directed jet openings leading into the sand trap for delivering liquid to the sand trap.

6. In a pump, the combination of a working barrel; a plunger operating in the barrel; a sand trap carried by the plunger and being in the form of an open cup; and a conduit for carrying liquid from the plunger extending through the cup, said cup having clearing passages connecting the cup with the main passage.

7. In a pump, the combination of a working barrel; a plunger operating in the barrel; a ring operating in connection with the tubing carried with the plunger; an open cup sand trap operating within the working barrel and carried by the plunger; and a conduit forming the main passage of the plunger carrying liquid from the plunger through the sand trap, said sand trap having clearing passages leading to the main passage.

8. In a pump, the combination of a working barrel; a plunger operating in the barrel, said plunger comprising a crown carrying the plunger valve; and a sand trap formed on the crown, said trap having clearing perforations connecting with the interior of the plunger.

9. In a pump, the combination of a working barrel; a plunger operating in the barrel, said plunger comprising a crown carrying the plunger valve; a sand trap formed on the crown, said trap having clearing perforations connecting with the interior of the plunger; and a ring above the plunger and carried with the plunger operating in connection with the tubing and working barrel for forcing liquid through the clearing perforations in the bottom of the sand trap.

10. In a pump, the combination of a working barrel; a plunger operating in the barrel; a main sand trap having in its upper end a ring operating in connection with the tube; and an auxiliary sand trap carried below the main sand trap and operating in connection with the working barrel, said auxiliary sand trap having clearing openings connecting with the interior of the plunger.

11. In a pump, the combination of a

- working barrel; a plunger operating in the barrel; and a sand trap carried with the plunger and having a portion extending into the working barrel and a portion extending above the working barrel, the portion above the working barrel having its greatest diameter greater than the diameter of the working barrel.
12. In a pump, the combination of a working barrel; a plunger operating in the barrel; a sand trap carried with the plunger and having a portion extending into the working barrel and a portion extending above the working barrel, the portion above the working barrel having its greatest diameter greater than the diameter of the working barrel; an open cup sand trap operating within the working barrel and carried by the plunger; and a conduit forming the main passage of the plunger carrying liquid from the plunger, said open cup sand trap having clearing passages leading to the main passage.
13. In a pump, the combination of a working barrel; a plunger operating in the barrel; a sand trap carried by the plunger; a main conduit in the plunger; and a tube connected with said conduit and leading upwardly from the sand trap, said tube having jet openings arranged at different levels in the sand trap.
14. In a pump, the combination of a working barrel; a plunger operating in the barrel; a sand trap carried by the plunger; a main conduit in the plunger; a tube connected with said conduit and leading up-

wardly from the sand trap; said tube having jet openings arranged at different levels in the sand trap; and a sucker rod connection arranged on said tube.

15. In a pump, the combination of a working barrel; a plunger operating in the working barrel; a sand trap carried by the plunger and being in the form of an open cup; a conduit for carrying liquid from the plunger extending through the cup, said cup having clearing passages connecting the cup with the main passage; and guide surfaces arranged in the cup adjacent to said clearing passages for guiding material to said passages.

16. In a pump, the combination of a working barrel; a plunger operating in the barrel; a ring operating in connection with the tubing carried with the plunger; an open cup sand trap operating within the working barrel and carried by the plunger; a conduit forming the main passage of the plunger carrying liquid from the plunger through the sand trap, said sand trap having clearing passages leading to the main passage; and guide surfaces arranged in the cup adjacent to said clearing passages for guiding material to said passages.

In testimony whereof I have hereunto set my hand in the presence of two subscribing witnesses.

RUDOLPH CONRADER.
